METHOD OF AND MACHINE FOR
CONVEYING CONCRETE

Ernst Bongardt, Mainz-on-the-Rhine, Germany

Application July 18, 1931, Serial No. 551,727, and
in Germany May 20, 1927

9 Claims. (Cl. 83—73)

The invention relates to method of and means for mixing, conveying and distributing concrete, mortar and the like.

Among the objects of the invention are to provide an improved means and method whereby this work can be economically and rapidly performed using a large volume of air at low pressure as the propelling agent.

The invention is embodied in the example herein shown and described.

In the accompanying drawings

Figure 1 is a side view of the hopper and breaker.

Fig. 2 is an elevation looking at the left hand side of Fig. 1.

Fig. 3 is a top plan view of what is shown in Fig. 1.

Fig. 4 is a vertical section of the breaker chamber and a portion of the screw.

Fig. 5 is a vertical section of the discharge end of the conveyor pipe.

Fig. 6 is a sectional detail on a larger scale of the water supply means.

Fig. 7 is a view looking into the right hand end of Fig. 6.

The apparatus for carrying out the invention includes the following: A hopper 10 into which the materials of the concrete are first supplied in a lightly moistened condition. In the chamber 11 of the hopper is a screw 12 on a driven shaft 12^a for feeding the materials.

The screw is somewhat spaced from the bottom of the hopper so as to allow an accumulation of cement and sand and thereby facilitate the action of the screw in feeding large gravel or pieces of stone into the chamber 13 now to be referred to. The chamber 11 opens into another chamber 13 into which the materials are fed, said chamber 13 having parallel vertical sides and to these sides are pivoted upper and lower compressor plates 15 and 16 each acted on by a roller on the ends of crank arms 17 and 18 on shafts 19 and 20 to press them toward each other. The lower one of the pressure plates has a downwardly bent flange to guide the material into the blowing line. The means for imparting the pressure to said rollers and plates consists of a pair of levers 21 and 22 fulcrumed on the external ends of a shaft 23, said levers each connected by links 24 and 25 with crank arms 26 and 27 carrying the internal roller-bearing crank arms 19 and 20. Each lever 21 and 22 has on its free end an adjustable weight 28 that can be adjusted and fixed thereon so that the pressure to be applied to the plates 15 and 16 can be varied to compact

to the desired degree the mass being fed into the chamber 13. The effect of the compressing plates is to form a tight plug of the materials and to substantially prevent the driving blast of air from backing into the screw chamber. A by-pass 40 is provided to balance the pressure in the chamber 13 with the main pipe line. Otherwise said chamber is made as tight as practicable, closures at the top and bottom being provided to afford access for cleaning.

Fixed on the shaft 12^a is a bladed breaker member 14 that cuts the compressed concrete mixture into small portions after it projects into the chamber 13.

30 designates the blower, the air discharge of which is connected with a pipe line 31 for conducting the concrete materials to the point where it is to be deposited. The pipe line 31 can be constructed of any suitable number of sections according to the work to be done, the last or discharging section being flexible so that it can be moved about to distribute the material discharged.

The chamber 13 discharges into the pipe line by means of a connecting conductor 13^a; and just below the point of intersection of the two is a hinged closure 31^a that can be opened to inspect and clear the interior of the pipe at and adjacent the junction of the pipe and conductor 13^a in case of clogging.

The air line from the conductor 13^a is located at a level somewhat below the level of the pipe from the pump to said conductor 13^a and a deflector is shown at 41 for diverting and contracting the air current in the pipe line across the lower end of the connecting conductor 13^a and into the line beyond the intersection of the conductor. The current of air and the concrete materials are thus moving in the same general direction.

The end of the pipe line 31 is equipped with an expanded chamber 32 composed of two conical portions connected at their bases by a narrow rim 33 provided with slots or openings 34; and a movable ring 35 is also provided with openings that can be slid around the rim 33 to partially or completely open said slots 34. The function of this chamber and its opening is to release the driving pressure on the materials prior to its final discharge as it is undesirable that the material should be discharged with great violence at the point of deposit. Beyond the said air or pressure release the momentum of the material is largely relied on to carry it to such point of discharge.

36 designates the nozzle section of the air line,

said section being preferably flexible to facilitate distribution of the materials. A flexible water supply pipe 37 provided with a regulating valve 37^a and a flared spray nozzle 38 is inserted between the flexible section and the air release, said water supply being extended inclinedly into the pipe line to discharge near the axis of the pipe and in the direction of movement of the concrete materials. Said nozzle is protected from the wearing action of the moving materials by means of an inclined shield 39.

The apparatus can be used for depositing concrete materials in either high or low places, as for example, in paving a street or making the floors in buildings.

In practice and in carrying out the method involved herein the concrete material is fed into the chamber in a quantity having a cross section equal to from one sixth to one tenth the cross section of the main pipe line. The concrete materials including the cement, gravel etc. are introduced into the apparatus fairly dry. For example, only about four gallons of water to one bag of cement or a hundred pounds of cement is used, or so that the water cannot evaporate and permit the material to settle onto the pipe line. If there be too much water some of the material is likely to settle on the bottom of the pipe line.

The pressure to be generated by the air blower is preferably from five to ten pounds according to the length of pipe and the height to which the material is to be carried. The volume of air should be about one hundred times the volume of the material, hence the material is moved rapidly with a large volume of air but at comparatively low pressure. Owing to its friction on the walls of the pipe the air travels fastest along the axis of the pipe thereby tending to entrain the material along said axis. The slower traveling air hugs the walls of the pipe and forms a bolster preventing the walls of the pipe from wearing out rapidly.

The quantity of water introduced at the discharge end of the pipe line is determined by the "slump" desired in the deposited materials, such slump varying according to the required type of work to be done. The materials are those ordinarily used but varied according to specifications particularly required.

The forms of the parts of the apparatus can be changed without departing from the gist of the invention as claimed.

What I claim is:

1. In apparatus for pneumatically mixing and conveying concrete materials, a hopper for said materials, a material feeding means in said hopper, a chamber with which said hopper communicates and into which the material is fed by the feeding means, and a pressure operated yielding means in said chamber beyond said feeding means for compressing the fed materials to form a plug of the material between the hopper and said chamber.

2. In apparatus for pneumatically mixing and conveying concrete materials, a hopper for said materials, a concrete feeding means in said hopper, a chamber with which said hopper communicates and into which the material is fed by the feeding means, a pressure operated yielding means in said chamber beyond said feeding means for compressing the fed concrete to form a plug between the hopper and said chamber, and bladed means in said chamber actuated by the feeding means for breaking said plug into portions within said chamber.

3. In apparatus for pneumatically mixing and conveying concrete materials, a blower and a pipe line, a hopper for the materials, a material feeding means in said hopper, a chamber with which said hopper communicates and into which the material is fed by the feeding means, said chamber discharging into the pipe line, a yielding pressure operated means in said chamber beyond said feeding means for compressing the fed concrete to form a plug between the hopper and said chamber, and a pressure balancing bypass pipe connecting the pipe line and said chamber at a point between the blower and the concrete discharge from said chamber. 80 85

4. In apparatus for pneumatically mixing and conveying concrete materials, a blower and a pipe line, a hopper for the concrete materials, a material feeding means in said hopper, a chamber into which said hopper communicates and into which the material is fed by the feeding means, a pressure operated resilient means for compressing the fed concrete to form a plug in said chamber beyond said feeding means, said chamber discharging the material by gravity into the pipe line, and a deflector in said pipe line 90 95 directing the blast of the blower into the materials in substantially the direction of their movement into the line. 100

5. In apparatus for pneumatically mixing and conveying concrete materials, a blower and a pipe line, a hopper for the concrete material, a material feeding means in said hopper, a chamber with which said hopper communicates and into which the material is fed by the feeding means, a pressure operated yielding means for compressing the fed concrete to form a plug between the hopper and said chamber, said chamber discharging the material by gravity into the pipe line, and a deflector in said pipe line directing and condensing the blast of the blower into the 105 110 materials in substantially the direction of their movement into the line. 115

6. In apparatus for pneumatically mixing and conveying concrete materials, a hopper for the material, a material feeding means in said hopper, a chamber with which said hopper communicates and into which the material is fed by the feeding means, a conveying pipe line connected with said chamber, yielding means for compressing the fed material to form a plug 120 between the hopper and said chamber, said pipe line having a discharge member spaced from the pipe line and a pipe line pressure relief consisting of an enlarged chamber connecting the terminus of the pipe line and said discharge member and surrounding the discharge terminus of the pipe line, said enlarged chamber provided with a perforated rim laterally remote from said terminus of the pipe line. 125 130

7. In apparatus for pneumatically mixing and conveying concrete materials, a hopper for the material, a material feeding means in said hopper, a chamber with which said hopper communicates and into which the material is fed by the feeding means, a conveying pipe line connected with said chamber, yielding means for compressing the fed material to form a plug between the hopper and said chamber, said pipe line having a discharge member spaced from the pipe line and a pipe line pressure relief consisting of an enlarged chamber connecting the pipe line and said discharge member and surrounding the discharge terminus of the pipe line, said enlarged chamber provided with a perforated rim laterally 135 140 145 150 155

remote from said terminus of the pipe line and an adjustable closure for said perforated rim.

8. In apparatus for pneumatically mixing and conveying concrete materials, a hopper for said materials, a material feeding means in said hopper, a chamber with which said hopper communicates and into which the material is fed, a pressure operated yielding means in said chamber beyond said feeding means for compressing the fed materials to form a plug of the material between the hopper and said chamber, and means whereby the pressure of said plug forming means may be varied.

9. In apparatus for pneumatically mixing and conveying concrete materials, a hopper for the material, a chamber with which said hopper communicates and into which the material is fed, a material feeding screw mounted to rotate in said hopper and chamber, a pressure operated yielding means in said chamber beyond said feeding means for compressing the fed materials to form a plug of the material in said chamber and a bladed member actuated with said feeding screw beyond said plug forming means to break up said plug into chunks. 80 85
